CONVEYER FOR BOTTLE CLEANING AND PASTEURIZING MACHINES

Ernest R. Becker, Oak Park, Ill., assignor to The
Liquid Carbonic Corporation, Chicago, Ill., a
corporation of Delaware

Application June 24, 1941, Serial No. 399,500

3 Claims. (Cl. 198—131)

This invention relates to bottle cleaning machines, and more particularly to the endless conveyors by means of which the bottles are conducted through such machines and subjected, during their transit therethrough, to various cleaning and/or pasteurizing operations. A type of endless conveyor which has gone into extensive use is one wherein the conveyor consists of side chains having bottle carriers extending transversely therebetween and secured thereto, with means for imparting intermittent movement to both side chains, thereby to advance the carriers and the bottles thereon through the bottle-cleaning machines, the means for imparting such intermittent motion consisting of pawls, mounted on opposite sides of the machines, and adapted to engage rollers carried by the side chains, with means for reciprocating the said pawls. The transverse bottle carriers which constitute part of such conveyors are connected at their ends to the inner members of the links of the side chains by means of end castings secured to said carriers. Heretofore the end castings have been connected to the inner members of the respective links of the side chains with their outer faces bearing directly against said members. Considerable difficulty has been encountered in time past in securing the outer faces of the end castings to the respective side chain members in such manner as to insure that the carriers shall extend accurately at right angles to the direction of travel of the conveyor, this failure being due to the presence of irregularities on these outer faces. This inability to obtain the necessary exact relation between the carriers and the chains causes misalignment of the carriers with respect to the various brushing and rinsing devices of the machines to the action of which the bottles are subjected by the movements of the conveyors.

A further difficulty, which has been due to this lack of exact relationship between the carriers and the chains, is that there is a tendency for one or the other of the pusher pawls to carry the full load of advancing the conveyors through the machines. While the outer faces of the end castings could be subjected to a machining operation, thereby to overcome this difficulty, this operation would add such a substantial amount to the cost of manufacture as to render recourse thereto very undesirable.

I have been able to utilize standard carriers, including their end castings, and at the same time to overcome any possibility of misalignment, by the construction shown in the drawing hereof,

wherein Fig. 1 represents a plan view of a portion of an assembled bottle conveyor having my invention embodied therein; Fig. 2 a sectional elevation corresponding to the line 2—2 of Fig. 1 and looking in the direction of the arrows; and Fig. 3 a detail, partly in plan and partly in section, of a portion of one of the side chains of my conveyor and showing the manner in which the end castings of the carriers are secured to the inner link members of the said chains.

Describing the various parts by reference characters, 10 denotes the side chains of a conveyor of the type referred to hereinbefore, each chain consisting of links comprising each an outer side member 11 and an inner side member 12. It will be noted that the link members 11 and 12 are spaced further apart at what I will refer to as their rear ends than at their front ends, said members being bent toward each other and then extending parallel with each other to provide a narrower space between the same at the front than at the rear. This is for the purpose of allowing the front ends of each link to be overlapped by the rear ends of the link in front thereof, as indicated clearly in the drawing. A roller 13 is mounted between the front ends of the members of each link and the rear ends of the members of the next adjacent link, being supported by a pin 14 extending through the overlapping portions of the links. It will be noted that the main bodies of the inner link members 12 of one of the opposed side chains are parallel with those of the other.

15 denotes a plurality of bottle carriers, each having a plurality of bottle-receiving pockets 16 suitably supported thereby. 17 denotes generally end castings which are secured to opposite ends of each carrier, as by means of bolts 18. Each end casting is provided with upper and lower flanges 19 and 20 adapted to receive the top and bottom edges of an inner link member therebetween and with a substantially plane outer surface 21 extending between said flanges which, in the carriers as heretofore constructed, has been bolted tightly against the adjacent face of a link member 12. The misalignment to which I have referred has been due to the presence of irregularities on these surfaces. In order to prevent such misalignment, I have provided each end casting with a counterbore 22 of spherical contour formed in the former seating surface of the casting and have fitted within said counterbore a spherical washer 23, said washer being of greater depth than the depth of the counterbore and the thickness of the washer being such as to

leave a slight clearance (preferably about $\frac{3}{16}$ inch) between the portion of the outer face of the end casting which surrounds the counterbore 22 and the adjacent surface 21 of the inner chain link 12. Each end of the carrier is secured to the chain adjacent thereto by means of a bolt 24 which extends through the link member 12 of such chain and through bores 23^a and 25, provided respectively in the washer 23 and in the end casting 11. It will be noted that the bores 23^a and 25 are of greater diameter than the diameter of the bolt, for a purpose to be described.

Each end casting is also provided with a longitudinally extending lug 26 having an opening 26^a therethrough for the reception of the end 14^a of the pin 14 which connects the front end of one chain link with the rear end of the other and which also supports a roller 13.

With the parts constructed and arranged as described, it is believed that the operation will be readily understood. The carriers having been assembled, the bolts 24 are pulled up moderately tight and locked by means of lock washers 27. Should any misalignment exist between any one or more of the carriers and the chain, when the parts are assembled, the operation of the pusher pawls 26, one on each side of the machine, will correct such misalignment during the initial running of the machine, the spherical contours of the washers and counterbores rendering the washers self-adjustable in their seats to an extent necessary to maintain parallelism between the opposed link members to which the carriers are secured. The enlargement of the bores 23^a and 25 (which enlargement is exaggerated in the drawing for purposes of illustration) will accommodate this correction of misalignment.

Having thus described my invention, what I claim is:

1. A bottle carrier comprising in combination side chains each having link members, carriers extending between opposed link members of said side chains and each provided with end extensions, each such extension having an outer surface provided with a seat of spherical contour

projecting inwardly therefrom, a washer having a plane outer surface, and a convex inner surface of spherical contour fitted within each of said seats, the plane surfaces of said washers projecting beyond the first mentioned outer surfaces, and means securing the end extensions of each of said carriers to their respective chain link members with the plane surfaces of the washers in engagement with their respective link members.

2. A bottle carrier comprising in combination side chains each having link members, carriers extending between opposed link members of said side chains, end members secured to the opposite ends of the said carriers, each of said members having an outer surface provided with a counterbore of spherical contour, a washer having a plane outer surface, and a convex inner surface of spherical contour fitted within each of the said counterbores, the plane surfaces of the washers extending beyond the first mentioned outer surfaces, and means securing the said end members to their respective link members with the plane surfaces of the washers in engagement with the adjacent surfaces of their respective link members.

3. A bottle carrier comprising in combination side chains each having link members, carriers extending between opposed link members of said side chains, and members secured to the opposite ends of the said carriers, each of said members having an outer surface provided with a counterbore of spherical contour, a washer having a plane outer surface, and a convex inner surface of spherical contour fitted within each of the said counterbores, with the plane surfaces of the washers extending beyond the first-mentioned outer surfaces, each end member having a bore extending inwardly from the bottom of the counterbore thereof and adapted to register with the bore of the washer therein, and bolts extending through the said bores and secured to the respective link members, the bores being of greater diameter than the said bolts.

ERNEST R. BECKER.
